(57) **CLAIM**

The ornamental design for a backpack with storage pouches, as shown and described.

DESCRIPTION

FIG. 1 is a perspective view of the backpack with storage pouches.

FIG. 2 is a front elevational view thereof.

FIG. 3 is a rear elevational view thereof.

FIG. 4 is a top view thereof.

FIG. 5 is a bottom view thereof.

FIG. 6 is a right side view thereof; showing the right side of the right strap of the backpack with storage pouches; and, FIG. 7 is a left side view thereof; showing the left side of the left strap of the backpack with storage pouches.

The broken lines showing in FIG. 1 through FIG. 7 illustrate portions of the backpack that form no part of the claimed design.

1 Claim, 6 Drawing Sheets
